UNITED STATES PATENT OFFICE.

DON COLE AND CHARLES J. GUSTAFSON, OF CHICAGO, ILLINOIS, ASSIGNORS TO STROMBERG MOTOR DEVICES COMPANY, OF CHICAGO, ILLINOIS, A CORPORATION OF ILLINOIS.

CARBURETOR.

Application filed June 19, 1914, Serial No. 845,999. Renewed October 16, 1922. Serial No. 594,901.

To all whom it may concern:

Be it known that we, DON COLE and CHARLES J. GUSTAFSON, respectively a citizen of the United States, and a subject of the King of Sweden, residing at Chicago, in the county of Cook and State of Illinois, have invented a certain new and useful Improvement in Carburetors, of which the following is a full, clear, concise, and exact 10 description, reference being had to the accompanying drawings, forming a part of this specification.

Our invention relates to carburetors for internal combustion engines, and it is directed to certain improvements with the object of securing an efficient mixture at all of the various suctions created by the engine.

The important features of our invention are a moving fuel nozzle, which moves toward and away from a substantially constant liquid fuel level, a special air valve construction, a special fuel valve construction, and certain features for the purposes of control. Our invention is concerned with 25 certain features of lesser importance, and is also concerned with certain combinations of the above enumerated elements alone, and also further combinations with additional carburetor parts.

Our invention is illustrated in the accompanying drawing which, in the main, is a longitudinal axial sectional view.

The main casing is illustrated at 1, and it will be seen that it is interiorly provided 35 with a Venturi tube 2, to which a main air inlet passage-way 3, leads. A manually operated valve 3^a controls this opening. The reference character 4 indicates the carbureting chamber generally, into which the 40 Venturi tube extends, and from which the outlet 5 is provided, this outlet being controlled by the usual throttle valve 6. As illustrated, the casing is provided with the flange 7 by means of which the carburetor 45 is attached to the engine manifold. A water jacket 8 is provided, as shown.

The main fuel nozzle 9 is mounted in a vertical stem 10, which is formed integrally with a bridge 11, extending diametrically 50 across the main air inlet passage. A shelf 12 supports a float chamber 13, which communicates with the nozzle 9 by means of a passage 14, and this float chamber maintains a level of liquid fuel approximately on

the dot and dash line x—x, being supplied 55 through the pipe 15.

The carbureting chamber 4 is provided with a side extension 16 in the top wall of which an opening 17 is provided. An annulus 18 is secured in said opening, and a bridge-piece 19 spans this annulus. The opening through this annulus is the auxiliary air opening.

A hollow stem 20 is hung from a head 21, which rests upon the top of the bridge-piece 19. The bottom of this stem is provided with a collar 21', and a spiral spring 22 rests upon this collar. A valve 23 is provided with a hollow stem 24, which surrounds the stem 20 and at the top of the 70 stem 24 there is provided an adjusting cup 25 within which the spring 22 engages. It will be seen now that the valve 23 is normally held upon its seat by means of the spring 22, and that the tension of this 75 spring may be varied by turning the cup 25, this cup being held in any adjusted position by a snap spring 26, which is carried by the valve, and which engages in any one of a plurality of grooves 27 in the periphery of 80 the cup. Rotation of the valve is prevented by the engagement of a pin 28 in a socket 29 in the part 19.

The hollow stem 24 extends downwardly through an aligned opening 25^a in the lower 85 wall of this part of the carbureting chamber, and passes into a dash pot 26^a aligned therewith, the bottom of this dash pot being closed by the cap 27^a.

A plunger 28^a arranged to reciprocate in the dash pot 27^a is secured to the bottom of the hollow stem 24 by means of a clamping screw 29^a, there being a clearance around the plunger. The interior of the dash pot communicates with the passage-way 14 by 90 means of the passage-way 30, which enters the dash pot just above the plunger 28^a, as shown.

A supplementary fuel nozzle 31 is inserted in the hollow stem 24 in a position in proximity to the fuel level line, as illustrated. This nozzle is fed through the hollow stem by way of the side passage-ways 32. It will now be seen that gasoline can travel upwardly from the dash pot, through the 105 hollow stem 24, through the nozzle 31, through the openings 21^a in the collar 21' on the stem 20, and through the annular

space in which the spiral spring 22 is disposed. A fuel discharge port 33, which is carried on the under side of the valve 23 and is directed toward the outlet from the carbureting chamber, communicates directly with this annular space, as shown.

A normally seated fuel valve 34 is secured in a stem 35, which is disposed in the hollow stem 20. A spiral spring 37 surrounds the 10 stem 35 within the hollow stem 20, and tends to keep the valve 34 seated in the nozzle 31.

The stem 35 is prevented from rotating within the hollow stem 20 by means of a 15 key screw 39. The stem 35 extends upwardly beyond the head 21 and has its end screw-threaded for the reception of a head 36, which head may thus be adjusted toward and away from the head 21. A pin 38 20 is secured in the head 21, and the head 36 is adapted to be held in any adjusted position by the engagement of said pin in any one of a plurality of openings 38^a in the flange on the head 36. It will be seen that 25 this is a very flexible arrangement, since the fuel valve 34 may thus be made to be either normally seated or normally unseated. We have illustrated it as being normally seated, and it will be noted that when the valve 23 30 opens, the time at which the fuel nozzle opens will depend upon the relation of the head 36 and the head 21. Thus, if it is desired to have the valve 23 open a short distance before the nozzle 31 is opened, the head 35 36 is so adjusted that normally it is a short distance above the head 21, as illustrated in the drawing. In such a case, it will be seen that under the influence of the spring 37, and gravity for that matter, the valve 34 40 will follow the downward movement of the nozzle 31 until the head 36 engages with the head 21 and, from then on, the nozzle 31 will be gradually opened wider as its downward movement continues. When it is desired to change the adjustment of the valve 34 either as to its normal position or as to the point at which the nozzle 31 is to open, in the opening of the valve 23, the head 36 45 is pulled upwardly to release it from the pin 38 and is then turned in the proper direction the desired amount, being then again dropped down on to the pin 38.

A lever 40, pivoted to the bridge-piece 19 at 41, is operated from the dash by means 55 of a wire 42 secured by means of a screw 42^a in a rotary head 42^b on the lever. This lever 40 has pivoted thereto, at 43, a link 44, which rides upon the top of the bridge-piece 19, and which has a cam surface 45 engaging 60 the under side of the head 21. When the lever 40 is swung about to the right, the head 21 is raised to increase the tension of the spring 22 and, later in this movement, the head 21 engages the head 36 to raise the 65 valve 34.

The dash adjustment, which has just been described, is used particularly on starting where it is desired to cut down the amount of air entering the carburetor, this being done by confining the entry of air to the 70 capacity of the main air inlet. At the same time, more fuel is made available and the rich mixture, desirable under these circumstances, is secured. As the operation of the engine proceeds, the springs and the valve 75 are allowed to come back to normal. In the starting operation the entry of air may be further restricted by means of the valve 3^a which may be closed down to limit the entry of air to that passing through the 80 clearance around it, but which is wide open in subsequent running.

For a certain range of suctions, after the starting function has been fulfilled, the main fuel inlet and air inlet provide the proper 85 mixture. However, it is well known that as the suctions are further increased, a mixture produced by the main air and fuel inlets alone would be too rich, and, therefore, diluting air or a diluting mixture is admitted 90 from the auxiliary air inlet or the auxiliary air inlet and the auxiliary fuel inlet. It will be noted that the auxiliary fuel inlet is located on the under side of the auxiliary air valve, and is directed toward the carburetor 95 outlet. The auxiliary air valve is operated by suction, but the influences which tend to hold it upon its seat are such that it does not respond until after a certain degree of suction has been attained. With the 100 auxiliary fuel inlet located as it is, the aspirating effect of the air entering through the auxiliary air inlet is very pronounced and the co-operation between the auxiliary fuel and the auxiliary air is especially effective. 105

The operation of the valve 23 is made smooth and even by the dash pot action which is provided for, and the valve may be said to be responsive to the effective suction of the engine as distinguished from all the 110 minute pulsations produced thereby. The valve 34 being properly adjusted for the purpose, the response of additional fuel is not coincident with the entry of additional air, but is slightly delayed in the interest of 115 the proper mixture at all suctions. After the valve 23 has been opened sufficiently to open the nozzle 31, the tapering of the valve and of the seat results in a gradual enlarging of the auxiliary fuel passage-way as the 120 air valve descends. Furthermore, an important action occurs, since the restriction in this auxiliary fuel passage-way, and for that matter the auxiliary fuel outlet itself, are brought down closer to the fuel level so as to require a lesser potential to cause an 125 issue from the auxiliary fuel inlet, thus working in harmony with the idea of getting more fuel as the suction increases, but at a properly controlled rate, so as to counteract 130

the tendency of the main fuel and air inlets to produce in themselves too rich a mixture at the higher suctions.

We claim as new and desire to secure by 5 Letters Patent:

1. In a carburetor, an automatic air valve, a fuel nozzle moving therewith, a valve for said fuel nozzle, means for adjusting the normal position of said valve, and temporary adjusting means for increasing the tension on said air valve and for raising said fuel valve later in the adjusting movement.
2. In a carburetor, an air inlet, a valve

for said inlet, a spring tending to hold said valve on its seat, a fuel nozzle, a valve for 15 said fuel nozzle, and a dash adjustment for increasing the tension of said spring and later in its movement for raising said fuel valve to open said fuel nozzle.

In witness whereof, we hereunto subscribe 20 our names, this 15th day of June, 1914.

DON COLE.

CHARLES J. GUSTAFSON.
